UNITED STATES PATENT OFFICE.

PAUL M. HOTCHKIN, OF CHICAGO, ILLINOIS, ASSIGNOR TO NATIONAL X-RAY
REFLECTOR COMPANY, OF CHICAGO, ILLINOIS, A CORPORATION OF ILLINOIS.

COMBINED JUNCTION-BOX AND REFLECTOR-CASING.

1,134,133.

Specification of Letters Patent.

Patented Apr. 6, 1915.

Application filed June 1, 1914. Serial No. 842,005.

To all whom it may concern:

Be it known that I, PAUL M. HOTCHKIN, a citizen of the United States, residing at Chicago, in the county of Cook and State of

5 Illinois, have invented certain new and useful Improvements in Combined Junction-Boxes and Reflector-Casings, of which the following is a specification.

My invention relates to lighting fixtures 10 for show-cases, bank-partitions and similar structures where it is found economical to employ such fixtures in integral units, as for example, in a show-case composed of a plate glass top and vertical walls and the fixtures 15 preferably disposed along the upper portions of said walls. In such installations it has been found expedient to employ a conduit in which the electric circuit wires are disposed and which has a plurality of junction boxes interposed throughout its length, 20 said boxes being so constructed that they are adapted to support the lamp sockets and reflector casings.

The particular object of my invention is 25 to produce a structure as above described in a manner so that after the elements have been assembled in the proper length to fit the show-case or the like, said assembled structure will be an integral unit and can 30 readily be mounted in proper position by any unskilled person without liability of error or miscalculation.

Another object is to produce an article of 35 this class that is economical to manufacture, can be sold at a reasonable price, and is neat in appearance and effective in operation.

These and numerous other objects I accomplish by the means and in the manner hereinafter fully described and as more particularly pointed out in the claims, reference being had to the accompanying drawings forming a part of this specification, wherein:

Figure 1 is a central vertical section of a 45 lamp socket reflector casing and reflector, illustrating the manner of mounting the same upon the junction box of an electric conduit; Fig. 2 is a longitudinal side elevation of the junction box having the reflector 50 and other parts removed; Fig. 3 is a transverse vertical section taken on line 3-3 Fig. 2.

Referring to the drawings, 5, 5, represent the longitudinally disposed axially alining

sections of a metal tube or conduit, through 55 which the wires of an electric circuit pass, that have their ends screw threaded and tapped into screw-threaded openings in the opposite ends of a metallic junction box. This junction box is preferably rectangular 60 in shape and comprises a hollow or shell-like body portion 6 that is provided with a central longitudinal cavity adjacent its arched or curved upper portion as shown. Said cavity communicates with the openings in 65 the end walls of the box and at about its center of length intersects with a lateral passageway 7 that passes axially through a short angular stub 8 projecting from one of the longitudinal sides of the body portion. 70 The bottom of the box is preferably open and is provided with a closure plate or cover 9 secured to the same by means of screws or the like.

Tapped into stub 8 is a relatively short 75 nipple 10 that is provided at the end of the screw-threaded portion with a shoulder or collar 11 made by increasing the diameter of the nipple so that when the latter is screwed into the stub said shoulder will abut against 80 the outer edge of the same. The outer end of the nipple is preferably the same diameter as the screw-threaded opposite portion and is adapted to be inserted into an opening made in the side wall of a cylindrical 85 shaped holder or container 12 and headed over as shown at 12*. This holder preferably forms a cap that covers and receives a lamp socket 13 of any approved or well known type in which a suitable electric lamp 90 or bulb 14 is adapted to be screwed as shown. The lower end of this cap is open so as to afford a means whereby a reflector casing 15 of any desired shape may be conveniently mounted and supported. I do not 95 desire to be confined to any particular shape or construction of reflector casing 15 or reflector 16 mounted therein for it is obvious that various types and shapes of the same are equally applicable.

In the drawing I have illustrated one 100 type for show-case lighting wherein the reflector casing is provided with a short angular portion 17 adjacent its upper end having its edge inturned to form a lip 18 as 105 shown, which portions 17 and 18 are adapted to enter cap 12 around the socket and to be secured to said cap by screws or other

wise. The casing preferably conforms in shape with the reflector which latter is retained within the same by means of a suitable spring or wire 19 that is snapped into the casing between the lower edge of the reflector and the inturned, flanged or beaded lower edge 20 thereto.

Having thus described my invention what I claim as new and desire to secure by Letters Patent, is:—

1. In a device of the kind specified, a tube provided with a suitable outlet mediate its ends, a cap, means for supporting said cap adjacent said outlet, a lamp socket within said cap, and devices for reflecting the light waves of said lamp provided with a portion adapted to be secured to said cap and to retain said lamp socket within said cap.
2. In a device of the kind specified, a tube provided with a suitable outlet mediate its ends, a cap, means for supporting said cap adjacent said outlet, a lamp socket within said cap, and devices for reflecting the light waves of said lamp provided with a portion adapted to fit within the open end of said cap and to be secured thereto and to retain said lamp socket within said cap.
3. In a device of the kind specified, a tube, a junction outlet box interposed therein mediate its ends, a cap indirectly carried by

said box, a lamp socket within said cap, and reflecting devices provided with a portion adapted to be secured to said cap and retain said socket within the latter.

4. In a device of the kind specified, a tube, 35 a junction outlet box interposed therein mediate its ends, a lateral member tapped into one of the walls of said box, a cap mounted on the outer end of said member and indirectly carried by said box, a lamp socket 40 within said cap, and reflecting devices provided with a portion adapted to fit within the open end of said cap and be secured thereto and retain said socket within the latter.

5. In a device of the kind specified, a conduit, a junction box interposed therein, one of the walls thereof provided with a lateral stub, a nipple tapped into said stub, 50 a cap carried by the outer end of said nipple having an open lower end containing a lamp socket, and a reflector casing having a portion adapted to be secured to said cap and to retain said lamp socket within said cap.

In testimony whereof I affix my signature 55 in the presence of two witnesses.

PAUL M. HOTCHKIN.
